FURNITURE FACING PANEL

Philip J. Rojahn, 1 E. Main St., Dallastown, Pa.

Filed Nov. 25, 1960, Ser. No. 62,970

Term of patent 14 years

(Cl. D33—1)

FIG. 1 is a front perspective view of a furniture facing panel, showing my new design.

FIG. 2 is a top edge plan view of said furniture facing panel showing my new design when applied to the front of a furniture drawer illustrated, in phantom.

FIG. 3 is a side elevation of said furniture facing panel showing my new design when applied to the front of a furniture drawer illustrated in phantom as in FIG. 2.

The essential feature of my design resides in an exposed furniture facing panel having front and rear plane surfaces with an exposed wedge-shaped edge therebetween and with the apex of the wedge extending outwardly from the panel, the forwardly facing surface of said wedge being at an acute angle to the central longitudinal plane of the panel and the rear surface of said wedge being at a less acute angle to the central longitudinal plane of the panel, all as shown.

The dot-dash lines included in FIGS. 2 and 3 of the drawing are for illustrative purposes only to represent adjacent surfaces of furniture upon which the present panel is applied.

I claim:

The ornamental design for a furniture facing panel, as shown and described.
